UNITED STATES PATENT OFFICE.

JAMES WILLIAM COLE, OF NASHVILLE, TENNESSEE.

OIL-STONE HOLDER.

SPECIFICATION forming part of Letters Patent No. 337,559, dated March 9, 1886.

Application filed February 24, 1885. Serial No. 156,776. (No model.)

To all whom it may concern:

Be it known that I, JAMES WILLIAM COLE, a citizen of the United States, residing at Nashville, in the county of Davidson and State of Tennessee, have invented a new and useful Improvement in Oil-Stone Holders, of which the following is a specification, reference being had to the accompanying drawings.

My invention relates to an oil-stone holder, and it has for its object to provide a device of this character whereby the oil from the stone will be prevented from running upon the work-bench or other place upon which it is used, as is usually the case with the oil-stone in ordinary use.

A further object of the invention is to provide an oil-stone holder which may be closed to exclude dust and other foreign matter from the stone, and to provide a holder which shall be cheap and simple in its construction and effective for the purposes intended.

With these ends in view the invention consists, primarily, in a box or casing provided on its bottom with a series of ribs to support the stone and to form spaces to serve as chambers for the reception of oil which may drip from the stone, and in means for securing the stone in place within the holder and to prevent its movement or displacement while being used.

The invention further consists in the details of construction and combinations of parts hereinafter fully described, and pointed out in the claims.

In the drawings, Figure 1 is a plan view showing the lid or cover thrown back and the stone clamped in position for use. Fig. 2 is a longitudinal vertical section on the line $x-x$ of Fig. 1, and Fig. 3 is a transverse vertical section on the line $y-y$ of Fig. 2.

In the accompanying drawings, in which like letters of reference indicate corresponding parts in all the figures, A represents a box or casing, which in the present instance has rounded ends, though, if desired, square ends could be employed to an equal advantage. Near one of the ends of the box or casing is provided a partition-wall, b, thus forming a chamber, a, which may be used for holding the oil-can.

Upon the bottom of the box or casing A are arranged a series of transverse ribs or strips, B, which are of a sufficient height to support

the oil-stone from the floor or bottom of the box or casing, and to form compartments or chambers for the reception of oil that may drip from the stone. On one of the sides of the box or casing are provided posts C, having screw-threaded holes or openings on their front faces near their upper ends, and fitting in said screw-threaded openings are set-screws D, having recesses or openings near their outer ends for the reception of any pointed instrument, whereby said set-screws may be turned. On the opposite inner side of the casing are provided inwardly-extending wings E, against the ends of which the oil-stone is adapted to bear when the set-screws on the box or casing are turned to tighten the same in place. A set-screw, F, working in a threaded opening of a post, G, is also provided at one end of the box or casing, while at the other end is provided an inwardly-extending wing, H, against which the end of the oil stone is adapted to bear.

I represents a lid or cover, which is hinged to the box or casing, and is provided with any suitable catch device, J, for holding it closed.

By the construction above described the oil-stone is firmly and securely clamped and held against either longitudinal or lateral movement, and by simply loosening the set-screws it may be instantly removed. The ribs or strips on the bottom or floor of the box or casing serve to support the stone from the said floor, thus forming a space for the oil which may drip from said stone.

By the use of the above-described holder the work-bench may at all times be kept free from the oil of the stone, which has heretofore been an annoying feature of its use, since, when the stone was simply mounted upon a block of wood, the oil escaped from the stone and ran upon the bench, and frequently upon the clothes of the user. By the construction before described these serious objections are overcome, and a holder provided which is not only cheap and simple in its construction, but one that is effective and thoroughly serviceable. Again, by placing the stone in a holder having the lid, so that it may be closed, dirt and other extraneous matter are excluded from the stone, which is an advantageous feature, since the dirt is apt to scratch and mar not only the stone, but the tools when they are being sharpened.

Having fully described my invention, what I claim as new, and desire to secure by Letters Patent, is—

1. The herein-described oil-stone holder, consisting of a box or casing having a series of ribs or strips upon its floor or bottom, a partition-wall forming a compartment for the reception of an oil-can, and devices for clamping the oil-stone against movement in the casing, substantially as set forth.

2. The herein - described oil-stone holder, comprising a case having a series of transverse ribs secured upon its bottom to form oil-chambers, a partition at one end adapted to form a

chamber for the reception of an oil-can, a standard at the opposite end of said case carrying a set-screw, a series of inwardly - projecting wings, E, at one side of the case, and two or more standards at the opposite side of the case carrying set-screws adapted to clamp the oil-stone, substantially as described.

In testimony that I claim the foregoing as my own I have hereto affixed my signature in presence of two witnesses.

JAMES WILLIAM COLE.
